UNITED STATES PATENT OFFICE.

ERNEST ULMO MACK, OF FLORENCE, SOUTH CAROLINA, ASSIGNOR
TO THE CROWN CORK AND SEAL COMPANY, OF BALTIMORE,
MARYLAND.

BOTTLING-MACHINE.

No. 813,562.

Specification of Letters Patent.

Patented Feb. 27, 1906.

Application filed November 11, 1904. Serial No. 282,550.

To all whom it may concern:

Be it known that I, ERNEST ULMO MACK, a citizen of the United States, residing at Florence, South Carolina, have invented certain new and useful Improvements in Bottling-Machines, of which the following is a specification.

My invention relates to bottling-machines for filling bottles with liquids of the general type disclosed in Letters Patent of the United States granted to William Painter, No. 608,158, dated July 26, 1898, and more particularly to means for centering the bottle in relation to the filling element. In said machine a syrup-nozzle is employed through which syrup is introduced into the bottle, for which purpose the bottle is placed on the table of the machine in position with its mouth below the nozzle, or approximately so, and the attendant by operating a treadle brings down the filling-head in order to cause the said nozzle to enter the mouth of the bottle for the discharge of the syrup thereinto.

My invention concerns means whereby, if through carelessness or haste the operator should not accurately position the bottle-mouth in line with the syrup-tube or if from any cause the bottle should be displaced, the descent of the filling-head will cause the accurate alinement of the bottle with the nozzle.

Further, my invention includes means whereby the bottle will be prevented from being raised off from the table when the filling-head rises.

The invention consists in the features and combination and arrangement of parts hereinafter described, and particularly pointed out in the claims.

The invention is illustrated in the accompanying drawings, in which—

Figure 1 shows a portion of a bottling-machine with my improvements associated therewith, the figure also showing a bottle in displaced relation to the nozzle and the improvement about to act on the said bottle to center it in relation to the nozzle. Fig. 2 is a detail view enlarged. Fig. 3 is a detail view of a modification.

In the drawings, 1 indicates the syrup-nozzle of the bottling-machine of substantially known form, having a nut 2 and a screw-threaded stem associated therewith, by which the nozzle may be secured to the filling-head in a manner substantially as shown in

the patent above referred to. Below the nut 55 2 a collar 3 is arranged, secured by a screw 4 to the nozzle, and from this collar a series of spring-fingers 5 depend, said fingers being screwed or otherwise secured to the collar 3. They extend down parallel with and at a 60 slight distance from the nozzle, and at their lower ends the springs are bent outwardly, forming inclined portions 6, the extreme lower ends of which are turned outwardly, as at 7. A loose collar 8 is located about the 65 lower end of the nozzle, and between this and the upper fixed collar there is interposed a spiral spring 9, tending constantly to force the loose collar downwardly. The flat springs or fingers 5 are slotted longitudinally from 70 the point 10 to the point 15, and through these slots pins 16 project, which pins are carried rigidly by the loose collar. Normally the loose collar is of course in its lowermost position, and the pins carried thereby are 75 resting on the lower walls of the slots at 15, and thus the said pins act as stops to determine the lowermost position of the loose collar, which is, as shown, slightly above the point of the nozzle. The drawings illustrate 80 the fact that when the bottle is placed beneath the filling-head and under the filling-nozzle it may be carelessly located with its opening out of line with the syrup-nozzle, and thus upon the descent of the filling-head the 85 nozzle would strike the lip of the bottle, resulting in breakage of the bottle and damage to the machine; but with my improvement the downwardly-projecting fingers, with their outwardly and downwardly inclined lower ends, 90 present means for centering or automatically adjusting the bottle in relation to the nozzle, so that before the point of the nozzle reaches the plane of the upper edge of the bottle-lip the bottle will have been shifted 95 so that the mouth thereof will be in alinement axially with the nozzle or in such a position that the downward movement of the nozzle will cause the same to enter the bottle-mouth, it being noted that the end of 100 the nozzle presents sloping or inclined sides and the mouth of the bottle being flared upwardly. The centering-fingers project slightly below the plane of the point of the nozzle, and thus they are in position to act 105 on the bottle and automatically center the same previously to the arrival of the point of the nozzle at the plane of the edge of the bot-

tle mouth or lip. As the filling-head continues to descend the nozzle will enter the mouth of the bottle, and the lip of said bottle will strike against the loose collar 8, and this will 5 slide upwardly along the nozzle, the spring 9 yielding for this purpose. When the syrup has been discharged into the bottle and the filling-head is raised, the collar 8 under the action of this spring will slide down along the 10 nozzle and will thus prevent the bottle from being raised from the table upon which it is supported when the filling-head rises. The bottle might under some circumstances be lifted up from the surface of the table when 15 the filling-head rises—such, for instance, because of the syrup causing the bottle to stick to the nozzle—but the sliding collar pressing downwardly as the nozzle rises will prevent such undesirable action. The connection 20 between the lower sliding collar and the spring-fingers, consisting of the pins of the collar projecting through the slots in the fingers, acts to steady the action of the fingers at their lower ends, serving to resist lateral 25 strain and displacement, the pins acting as guides, so that the spring-fingers will yield in a radial direction.

It is desirable to preserve or maintain as much head room or space between the lower 30 end of the nozzle and the top thereof to allow the nozzle to enter to the maximum degree into the bottle, and I therefore form the collars 3 and 8 of as little height as possible consistent with strength. In order to get more 35 head-room than that which would be allowed by the use of the collars, I employ the connection illustrated in Fig. 2, in which in place of the upper collars secured to the nozzle I support the spring-fingers upon an annular 40 flange or ring associated with the nut 2. This ring may be held within a flange depending from the nut by means of screws 17, the said ring being indicated at 18. This arrangement will allow the head of the bottle 45 to rise within the ring and close up against the under side of the nut. This is important in a machine of this character to accommodate different heights of bottles.

I claim as my invention—

50 1. In combination in a bottling-machine, a nozzle adapted to enter the bottle-mouth and resilient means for centering the bottle in relation to the nozzle, said means extending down along the nozzle and acting as the nozzle and bottle are brought together, substantially as described.

2. In combination, in a bottling-machine, a nozzle and a spring finger or fingers supported at their upper ends with their lower ends free, 60 said fingers being associated with the nozzle for engaging the bottle and centering the same in relation to the nozzle as the nozzle and bottle are brought together, substantially as described.

65 3. In combination in a bottling-machine, a

nozzle, a spring finger or fingers depending from an upper point or support along the nozzle and having outwardly and downwardly inclined lower free ends for engaging the bottle and centering the same in relation to the nozzle. 70

4. In combination in a bottling-machine, a nozzle adapted to enter the bottle, and a sliding collar on the said nozzle with a spring for pressing the said nozzle downwardly to 75 prevent the lifting of the bottle as the nozzle is withdrawn therefrom and a plurality of spring-fingers between which the collar slides, substantially as described.

5. In combination in a bottling-machine, a 80 nozzle, a centering finger or fingers depending below the same to contact with the bottle, a collar adapted to slide on the nozzle, a spring for pressing the collar downwardly and a stop associated with the collar and centering-finger, substantially as described. 85

6. In combination, the nozzle, the sliding spring-pressed collar, the centering-fingers and the sliding connection between the said fingers and the collar, substantially as described. 90

7. In combination, the nozzle, the centering-fingers slotted vertically, a spring-pressed collar having pins projecting from the collar through the slots in the fingers, substantially 95 as described.

8. In combination with the nozzle, a spring-pressed collar thereon and means for limiting the downward movement of the collar consisting of the finger or arm between which and the nozzle the lip of the bottle is adapted to move, the said collar having a connection with the said arm or finger, substantially as described. 100

9. In combination in a bottling-machine, a 105 nozzle adapted to enter the bottle-mouth, and means for centering the bottle in relation to the nozzle, said means being yielding laterally in relation to the nozzle, substantially as described.

10. In combination in a bottling-machine, a nozzle adapted to enter the bottle-mouth, and means for centering the bottle in relation to the nozzle, said means comprising a plurality of members individually yieldable radially in respect to the nozzle, substantially as described. 110

11. In combination in a bottling-machine, a nozzle adapted to enter the bottle-mouth, and a plurality of fingers depending along the nozzle and individually yieldable radially in respect to the nozzle, substantially as described. 115

In testimony whereof I affix my signature in presence of two witnesses.
